UNITED STATES PATENT OFFICE.

WILLIAM J. WHARTON, OF WASHINGTON, DISTRICT OF COLUMBIA.

PRIVY.

SPECIFICATION forming part of Letters Patent No. 380,540, dated April 3, 1888.

Application filed January 13, 1888. Serial No. 260,653. (No model.)

To all whom it may concern:

Be it known that I, WILLIAM J. WHARTON, a citizen of the United States, and a resident of Washington, in the District of Columbia, have 5 invented certain new and useful Improvements in Privies; and I do hereby declare that the following is a full, clear, and exact description of the invention, which will enable others skilled in the art to which it appertains to make and 10 use the same, reference being had to the accompanying drawings, which form a part of this specification, and in which—

Figure 1 is a plan view of a privy or water-closet such as is usually found in railway-cars. Fig. 2 is a vertical cross-section of the same on the line denoted by *xx* in Fig. 1. Fig. 15 3 is a vertical transverse cross-section of Fig. 2. Fig. 4 is a modified form of my invention, and Fig. 5 is a detail perspective view of the 20 brace at the lower end of the lifting-rod.

Like letters of reference denote corresponding parts in the several figures.

My invention has relation to privies or water-closets which are intended more particularly for use on railway-cars, and has for its 25 object to so construct these privies that they may be used continuously, whether the car is in motion or is at a standstill at a station.

In order to fully understand the nature and 30 object of my invention it may be well to invite attention to the fact that the municipalities of nearly all the cities and towns through which railway-tracks are laid for the passage of trains have established ordinances, which 35 are rigidly enforced, compelling railway companies to see that the doors of the car-privies are closed while the train is waiting at a station and while, in leaving or arriving at the 40 station, it passes through the streets of the town or city. The reason of such ordinances is obvious, but is nevertheless a great inconvenience to the passengers occupying the car, and especially to invalids, who often suffer 45 great pain and inconvenience because they cannot have access to the water-closet, however urgent their needs may be.

Now the object of my invention is to so construct the privies or water-closets that there will be no need of denying the passengers access to and use of the same at any time. In 50 other words, the door of the closet need not

be locked; but the closet may be available at all times, whether the train is standing still at a station or whether it has passed through the public thoroughfares of the town or city. 55

The advantages of this improvement are so obvious as to not require recapitulation. It will prevent the distress caused by forcing passengers to wait probably for a considerable time, and while it will thus relieve the occupants of a railway-car from physical anguish and inconvenience it will at the same time relieve the railways of the annoyance of having claims for damages presented against them resulting from the illness and from other causes 65 which often result from the practice of locking the privy-doors against passengers.

Referring to the accompanying drawings, the letter A denotes the floor of the privy of a railway-car, and B the outer wall of the same, 70 which is usually formed by one side of the car-body and provided with a window, C.

D denotes the roof of the closet, which is usually also the roof of the car, and E and F indicate the transverse partitions which, with 75 the rear wall, B, and front partition, G, form the closet, said front partition being provided with the usual door, H. Of course the closet may be located in any convenient part of the car and the position of the door and window 80 may be altered to suit varying conditions and circumstances, as these form no part of my improvement.

The letter I' denotes the seat of the closet, which is provided with a bowl, I, of any desired shape, construction, and material. The lower part or outlet of this bowl projects downwardly through the floor A in the usual manner, and below the outlet of the same is arranged a movable vessel or receptacle, J, 90 swinging on a hinge, K, which is fastened to the support L. When this swinging receptacle is in its closed or operative position, as shown in full line in the drawings, it will be immediately below the outlet of the bowl I and will 95 form a receiver or receptacle for any matter deposited in the bowl. When, however, the receptacle J is swung into the position indicated by the dotted lines, it will be seen that it is placed at such an angle that its contents 100 may be readily emptied, and at the same time it will be withdrawn from the outlet of bowl I,

so that any matter deposited in the bowl when the movable receptacle is in this position will be deposited upon the ground beneath the car.

In practice the receiver or receptacle J should be made of sufficient capacity to hold a reasonable amount of matter without any danger of overflow. Inside of the closet is also arranged, at any convenient point, the usual urinal, M, the spout of which (denoted by the letter N) extends below the floor of the closet into a swinging receiver (denoted by the letter J') which is in all essential respects a counterpart of the swinging receiver J, already described. Like the receiver J, this second receptacle, J', is attached, by means of a hinge, K', to a fixed support, L', fastened to any suitable part of the car-body. When the receiver J' is in its closed position, as indicated in the drawings, it will receive the fluid which is poured through the urinal M and its spout N, whereas when it is swung into the position indicated in dotted lines it will be in such a position as to readily empty itself, and in that position it will be seen that the lower end of the spout discharges directly upon the ground below the car.

The two hinged and movable receivers J and J' are operated as follows: A stout rod or bar, O, confined within suitable guides or keepers, P P, projects through an aperture in the floor of the car and is provided at its upper end with a suitable handle, Q. For the sake of convenience this handle may rest in a recess or depression in the floor and is held in this position by means of a latch, R, pivoted on the car-floor. At the lower end of rod O, projecting at right angles from the same, is a bracket, S, at the outer end of which is a horizontal arm, T. The bracket S and arm T are suitably braced to give them the desired amount of stiffness and rigidity, so as to prevent them from bending. One end of arm T extends in the hinged receiver J and the other arm extends in the direction of the hinged receiver J'.

Two arms or connections (denoted, respectively, by the reference-letters U U') are hinged or pivoted to the opposite free ends of arm T, and are connected pivotally to the receivers J and J', respectively, by the joints or hinges V and V'. When the rod O is in the position shown in full line on the drawings—that is to say, when it is lowered to its full capacity—the arm T, in conjunction with the connecting-brackets U and U', will form a stiff brace, holding the receptacles J and J' in their closed position, so that these cannot possibly swing back upon their hinges. On the other hand, when this rod is folded up, so as to occupy the position indicated in dotted lines, the hinged brackets or connections U and U' will pull upon the receptacles to which they are respectively connected, so as to swing these back into the positions indicated in dotted lines, in which positions, as we have already seen, they will be freely emptied of their contents, at the same time opening the outlet for the bowl I and

spout N. In order to retain the receptacles J and J' in this open position, I employ any suitable means—such as a hook or latch—adapted to engage the handle Q, and thereby prevent the rod from slipping down through the floor.

Instead of employing two separate receivers, as shown in Figs. 1 and 3, the spout N may, after it passes through the floor, be carried to one side, so as to overlap the receptacle J, as shown in Fig. 4, and when this construction is employed it is obvious that I dispense with the receptacle J', making the receptacle J do duty for both purposes. In that case, however, this receptacle J should be made of sufficient capacity to answer both purposes—viz., to act as a tank or receptacle for matter deposited not only through the bowl I, but also through the urinal.

While in the drawings I have shown an operating-rod, O, adapted to be raised by hand, which may easily be done, as it requires only very little force to work it, yet it is obvious that a system of levers may readily be arranged for working this rod O up and down, thereby reducing the force necessary for operating the device. As this arrangement of levers will readily suggest itself to any skilled mechanic, I have not deemed it necessary to illustrate it on the drawings, in which I have illustrated only what I conceive to be the essential features of my improvement.

In practice I prefer to construct the downwardly-projecting supports L and L', to the lower part of which the reversible receivers J and J' are respectively hinged, in the nature of a drum or cylinder, the upper rim of which is attached to the floor, while the lower edge or rim is of such a size and configuration that it will correspond in shape to the shape of that part of the reversible receptacle which, when it is closed, impinges upon its lower rim. Of course the hinged receptacles need not be connected to the cylinders L or L', but may be hinged to any other suitable supports if it should be found inconvenient to hinge them directly to said cylinders. When the receptacles J and J' are closed, as indicated in full line in the drawings, they will impinge closely upon the lower rim or rims of said cylinders L and L', so as to form a practical tight joint. This is for the purpose of preventing splashing of the contents of said receptacles while in their closed position, and, if desired, a gasket of rubber or any other suitable elastic material may be arranged around the lower part of the cylinders L and L' for the purpose of effecting a tight joint, or any other suitable means may be employed for making the joints practically tight and prevent splashing or spilling of the contents of the receptacles while the cars are in motion before it is time to open the same for the purpose of emptying them of their contents. These downward projections or cylinders (although they need not by any means be cylindrical in shape, although for convenience I term them "cylinders") con-

stitute an important feature in my invention, inasmuch as without them the fluid contents of the receptacles will be apt to spill or splash; but by closing them tightly against the lower 5 rim of said cylinders such splashing or spilling is absolutely prevented. The length of these downward projections L and L' will of course depend upon the particular construction of the car to which my invention is to be applied.

10 In practice the operation of this device is as follows: When the car enters the precincts of a town or city, the brakeman, instead of locking the door to the closet, as is now the practice, simply enters the same, and by lowering 15 the rod O swings the receptacles J and J' into their closed position underneath the bowl I, casing L, and spout N. Owing to the arrangement of the arm or brace T and connecting-braces U and U', the said receptacles will be 20 held fixed in this position without possibility of their swinging back of their own accord. In this position it will be seen that all matter deposited through the bowl I and the urinal L will not be deposited upon the ground, but 25 will be received and stored in the respective receptacles, from which said contents are prevented from splashing over by means of the casing, L and L', against the lower edges of which said receptacles respectively impinge.

30 When the train again starts, and after it shall have left the outskirts of the city, all the brakeman has to do is simply again to enter the closet, and, by raising the rod O, reverse the receptacles J and J', so as to empty the same 35 and afford a free outlet for the bowl and urinal-spout. Thus it will be seen that the occupants of the car can have free access and use of the closet at any time during their stay in the car, even when it is standing still within 40 a railway-depot.

While this improvement is designed especially for use on railway-cars, I desire it distinctly understood that I do not desire its application limited to that particular purpose, as it may be employed with advantage for 45 many other purposes—for example, on ship-board, in private residences, or under other conditions where it is desirable to have such an arrangement. The most urgent need for such a contrivance, however, appears at present to 50 be in the construction of railway-cars, both ordinary passenger-coaches, sleeping-cars, and so-called “drawing-room” cars.

Having thus described my invention, I claim and desire to secure by Letters Patent of the 55 United States—

1. The combination, with the privy-bowl I and its outlet, of the hinged tank or receptacle J, arranged below the same, a movable joint or connecting-rod, and a vertical reciprocating rod provided at its lower end with a right-angled arm or brace connected pivotally to the movable joint or connecting-rod, substantially as shown and set forth.

2. The combination of the swinging receptacles J J', jointed lock-connections U U', pivoted thereto, the arm T, pivoted at each end to the said lock-connections, and a vertically-reciprocating rod secured to the intermediate portion of said arm, substantially as 60 65 70 and for the purpose shown and set forth.

In testimony that I claim the foregoing as my own I have hereunto affixed my signature in presence of two witnesses.

WILLIAM J. WHARTON.
